CLAIM

The ornamental design for an identification tag, as shown and described.

DESCRIPTION

FIG. 1 is a perspective view of an identification tag, showing my new design;

FIG. 2 is a front elevational view thereof;

FIG. 3 is a right side elevational view thereof, the left side view being substantially a mirror image thereof;

FIG. 4 is a rear elevational view thereof; and

FIG. 5 is a top plan view thereof.
